(No Model.)

C. J. DOBBS.
BRICK FOR PAVING.

No. 374,118.

Patented Nov. 29, 1887.

UNITED STATES PATENT OFFICE.

CHARLES JAMES DOBBS, OF MIDDLESBROUGH, COUNTY OF YORK,
ENGLAND.

BRICK FOR PAVING.

SPECIFICATION forming part of Letters Patent No. 374,118, dated November 29, 1887.

Application filed December 23, 1886. Serial No. 222,385. (No model.) Patented in England August 24, 1886, No. 10,829.

To all whom it may concern:

Be it known that I, CHARLES JAMES DOBBS, a citizen of England, residing at Middlesbrough, in the county of York, England, have 5 invented a new and useful Improved Manufacture of Scoria Paving-Blocks, (for which I have obtained a patent in Great Britain, No. 10,829, dated August 24, 1886,) of which the following is a specification.

10 Paving-blocks made of blast-furnace scoria or slag have the disadvantage that by the chilling action of the mold in which they are cast the outer skin assumes a very hard smooth texture that tends to slipperiness. According 15 to my present invention I so manufacture such blocks that, instead of presenting the hard skin of the block as the wearing-surface, I present a fractured surface of the block, which does not possess the glassy texture of the skin. For 20 this purpose I form the molds for the blocks of sufficient size to make two or more blocks, and at the part of the mold corresponding to the division of the blocks into separate lengths I form projecting ribs or fillets on the bottom 25 and sides of the mold, having a V shape, and I also place across the top of the mold a V-shaped bar, so that on running in the liquid slag a V-shaped groove is formed all round the block. After this has solidified and has been 30 annealed in the usual manner, I subject the block to a blow, whereby it will be fractured at the point where the groove has been formed, and this more or less rough fractured surface I then use as the wearing-surface of the block.

35 Figure 1 of the accompanying drawings shows a perspective view of a double slag-block cast with V-shaped grooves *a a*, as above described; and Fig. 2 shows one-half of the block after being fractured across the grooved 40 part, so as to produce a rough fractured surface, *b*, for the wearing-surface. Fig. 3 shows a transverse section of the form of mold which I employ, by preference, for forming the grooved double block. Fig. 4 shows the same view 45 with the mold opened. Fig. 5 shows a sectional front view of the mold.

The mold is formed of two separate parts, *c d*, hinged together at *e*, the part *c* being fixed

to a turn-table, on the periphery of which a number of such molds are fixed. The two 50 parts are held together in the closed position shown by the catch *f*, thus forming a rectangular box, in which are projecting V-shaped fillets *g g g*, and also a V-shaped bar, *g'*, fixed to the part *c* and projecting across the open top 55 of the mold. The one side, *h*, of the mold (shown in dotted lines in Figs. 3 and 4) is also formed on the part *c* and serves as the attachment to the turn-table, while the other side, *h'*, and the bottom *h''* are formed on the part *d*. The liquid slag being run into the mold and having solidified, the catch *f* is released, whereupon the part *d* of the mold, with the block in it, will drop into the position shown at Fig. 4, when the block will fall out, having the configuration shown in Fig. 1.

Although I prefer to cast the blocks with a V groove on all four sides, yet a single groove or two grooves on opposite sides may be sufficient.

I am aware that tiles, wall-coping, and similar articles of terra-cotta have been molded with grooved division-lines, along which the article or articles can be subsequently separated; but this I do not broadly claim, and my 75 invention differs therefrom in that it embraces only a paving-block of scoria having a roughened wearing-surface produced by fracturing a double block of such material.

Having thus described the nature of my invention and the best means I know for carrying the same into practical effect, I claim—

As an improved article of manufacture, a scoria paving-block having a roughened fractured wearing-surface, substantially as described.

In testimony whereof I have signed my name to this specification, in the presence of two subscribing witnesses, this 7th day of December, A. D. 1886.

CHARLES JAMES DOBBS.
